ABSTRACT

A new *Chrysanthemum* plant named 'Synjac Pinka' particularly distinguished by the small to medium sized flowers with light red-purple ray florets, dark yellow-green foliage, a garden *Chrysanthemum* with uniform ball-shaped plant habit and a natural flowering season of about mid-September.

1 Drawing Sheet

1

Latin name of the genus and species of the plant claimed:
Chrysanthemum×morifolium.

Varietal denomination: 'Synjac Pinka'.

BACKGROUND OF THE NEW PLANT

The present invention comprises a new *Chrysanthemum*, botanically known as *Chrysanthemum×morifolium*, and hereinafter referred to by the variety name 'Synjac Pinka'.

'Synjac Pinka' is a product of a planned breeding program. The new cultivar has small to medium sized flowers with light red-purple ray florets, dark yellow-green foliage, a garden *Chrysanthemum* with uniform ball-shaped plant habit and a natural flowering season of about mid-September.

'Synjac Pinka' originates as a natural whole plant mutation of 'Yojacquelle', U.S. Plant Pat. No. 18,927 and was discovered in an outdoor controlled breeding trial and selected by the inventor as a single flowering plant within a population of the parent cultivar in Alva, Fla. in November 2006. The parent cultivar 'Yojacquelle' has two-toned pink ray florets with a faster natural flowering season response.

The first act of asexual reproduction of 'Synjac Pinka' was accomplished when vegetative cuttings were propagated from the initial selection in December 2006 in a controlled environment in Alva, Fla.

BRIEF SUMMARY OF INVENTION

Horticultural examination of plants grown from cuttings of the plant initiated in December 2006, and continuing thereafter, has demonstrated that the combination of characteristics as herein disclosed for 'Synjac Pinka' are firmly fixed and are retained through successive generations of asexual reproduction.

'Synjac Pinka' has not been observed under all possible environmental conditions. The phenotype may vary significantly with variations in environment such as temperature, light intensity and day length.

A Plant Breeder's Right for this cultivar was applied for in Canada on Oct. 30, 2009 (09-6769). 'Synjac Pinka' has not been made publicly available more than one year prior to the filing of this application.

2

The following traits have been repeatedly observed and are determined to be basic characteristics of the new variety. The combination of these characteristics distinguishes this *Chrysanthemum* as a new and distinct variety.

5 BRIEF DESCRIPTION OF THE PHOTOGRAPHS

The accompanying photographic drawing shows typical flower and foliage characteristics of 'Synjac Pinka' with colors being as true as possible with an illustration of this type. The photographic drawing shows a flowering potted plant of the new variety, and a close-up of the flowers.

DETAILED BOTANICAL DESCRIPTION

15 The plant descriptions and measurements were taken in Gilroy, Calif. in May 2010 under natural light. These plants were about 10 weeks old.

20 The aforementioned photographs were taken in Gilroy, Calif. in late October 2009 outdoors. These plants were approximately 12 weeks of age.

Color references are made to The Royal Horticultural Society Colour Chart (R.H.S.) 2001.

25 TABLE 1

DIFFERENCES BETWEEN THE NEW VARIETY 'SYNJAC PINKA' AND A SIMILAR VARIETY: 'YOURSULA'
(U.S. Plant Pat. No. 13,641)

		'Synjac Pinka'	'Yoursula' (U.S. Plant Pat. No. 13,641)
30	Ray floret quantity:	Fewer	More
	Disc floret quantity:	Less	More
	Plant size/habit:	Little larger/rounder	Smaller/less round
35	Natural flowering season response:	Couple days slower	Couple days faster
	Shaded response:	Couple days faster	Couple days slower

Plant:

Form, growth and habit.—Herbaceous decorative garden type; Stems upright and outwardly spreading, freely branching, strong and moderately vigorous growth habit.

<i>Plant height.</i> —12-14 cm.		<i>Mature inflorescence:</i>
<i>Plant height (inflorescence included).</i> —15-17.5 cm.		<i>Diameter.</i> —3.5-4.0 cm.
<i>Plant width.</i> —21-24 cm.		<i>Depth.</i> —2.0 cm.
<i>Garden performance and tolerance to weather.</i> —Very good.	5	<i>Total diameter of 'disc'.</i> —0.2 cm.
<i>Roots:</i>		<i>Receptacle height.</i> —0.5 cm.
<i>Number of days to initiate roots.</i> —4 days at about 22 degrees C.		<i>Receptacle diameter.</i> —1.2 cm.
<i>Number of days to produce a rooted cutting.</i> —10-12 days at 22 degrees C.	10	<i>Ray florets:</i>
<i>Type.</i> —Fine, fibrous, free branching.		<i>Average quantity of florets.</i> —About 60 in numerous whorls.
<i>Color.</i> —RHS N155B but whiter.		<i>Color of florets, upper surface.</i> —RHS 75C with more RHS 70B overlay and less of RHS 72B overlay.
<i>Foliage:</i>		<i>Lower surface.</i> —RHS 75B to RHS 75C.
<i>Arrangement.</i> —Alternate, simple.		<i>Length.</i> —1.9-2.1 cm.
<i>Immature, leaf color, upper surface.</i> —Closest to RHS 147A.	15	<i>Width.</i> —0.4 cm.
<i>Lower surface.</i> —Lighter than RHS 147A.		<i>Shape.</i> —Oblong to elliptical.
<i>Mature, leaf color, upper surface.</i> —Closest to RHS 147A.		<i>Apex shape.</i> —Praemorse.
<i>Lower surface.</i> —Lighter than RHS 147A.	20	<i>Margin.</i> —Entire.
<i>Length.</i> —2.7-2.9 cm.		<i>Texture, upper surface.</i> —Papillose.
<i>Width.</i> —2.0-2.5 cm.		<i>Lower surface.</i> —Papillose.
<i>Shape.</i> —Broadly ovate.		<i>Disc florets:</i>
<i>Base shape.</i> —Attenuate.		<i>Average quantity of florets.</i> —About 35.
<i>Apex shape.</i> —Mucronulate.		<i>Color of florets.</i> —RHS 11B to RHS 11C with RHS 3A apex.
<i>Margin.</i> —Palmately; irregularly lobed; sometimes 25 irregularly serrate.		<i>Length.</i> —0.5 cm.
<i>Texture, upper surface.</i> —Bifid T-shaped hairs.		<i>Width.</i> —0.1 cm.
<i>Lower surface.</i> —Bifid T-shaped hairs.		<i>Shape.</i> —Tubular, elongated.
<i>Color of veins, upper surface.</i> —RHS 146C.		<i>Apex shape.</i> —Acute, 5 pointed.
<i>Color of veins, lower surface.</i> —RHS 146C.	30	<i>Phyllaries:</i>
<i>Petiole color.</i> —RHS 146C.		<i>Quantity.</i> —25-30.
<i>Length.</i> —0.4-0.9 cm.		<i>Color, upper surface.</i> —RHS 146A to RHS 146B.
<i>Diameter.</i> —0.2-0.3 cm.		<i>Lower surface.</i> —RHS 147B.
<i>Texture.</i> —Bifid T-shaped hairs.		<i>Length.</i> —0.3-0.4 cm.
<i>Stem:</i>		<i>Width.</i> —0.1-0.2 cm.
<i>Quantity of main branches per plant.</i> —About 8-10.	35	<i>Shape.</i> —Ovate.
<i>Color of stem.</i> —RHS 147B.		<i>Apex shape.</i> —Acute.
<i>Length of stem.</i> —8.0-9.0 cm.		<i>Based.</i> —Fused.
<i>Diameter.</i> —0.3 cm.		<i>Margins.</i> —Entire.
<i>Length of internodes.</i> —0.5-0.8 cm.		<i>Texture, upper surface.</i> —Glabrous.
<i>Texture.</i> —Bifid T-shaped hairs.	40	<i>Lower surface.</i> —Bifid T-shaped hairs.
<i>Color of peduncle.</i> —Closest to RHS 147B.		<i>Reproductive organs:</i>
<i>Length of peduncle.</i> —3-4.5 cm.		<i>Pistil (presence on disc and ray florets).</i> —1.
<i>Peduncle diameter.</i> —0.15-0.2 cm.		<i>Length.</i> —0.4 cm.
<i>Texture.</i> —Bifid T-shaped hairs.	45	<i>Style color.</i> —RHS 1B.
<i>Inflorescence:</i>		<i>Style length.</i> —0.3 cm.
<i>Type.</i> —Compositae type, solitary inflorescences (decorative-type) borne terminally above foliage, ray florets arranged acropetally on a capitulum.		<i>Stigma color.</i> —RHS 3A.
<i>Natural season flowering.</i> —About mid-September.	50	<i>Stigma shape.</i> —Bi-parted.
<i>Quantity of inflorescences per plant.</i> —About 30-40 plus numerous buds.		<i>Ovary color.</i> —Not observed.
<i>Lastingness of individual bloom on the plant.</i> —3-4 weeks.		<i>Stamens (presence on disc florets only).</i> —1.
<i>Fragrance.</i> —Very slightly spicy.		<i>Color of filaments.</i> —RHS 1B.
<i>Bud (just when opening/showing color):</i>		<i>Length filaments.</i> —0.2 cm.
<i>Color.</i> —RHS 70B.		<i>Anther color.</i> —RHS 3A.
<i>Length.</i> —0.8-1.0 cm.		<i>Anther length.</i> —0.1 cm.
<i>Width.</i> —0.7-0.8 cm.		<i>Anther shape.</i> —Oblong.
<i>Shape.</i> —Oblate.		<i>Color of pollen.</i> —Not observed.
<i>Immature inflorescence:</i>		<i>Pollen amount.</i> —Not observed.
<i>Diameter.</i> —2.5-3.0 cm.		<i>Fertility/seed set.</i> —Has not been observed on this hybrid.
<i>Color of ray florets, upper surface.</i> —RHS 75C with more RHS 70B and RHS 72B overlay.	55	<i>Disease/pest resistance:</i> Disease/pest resistance has not been observed on this hybrid.
<i>Lower surface.</i> —RHS 75B to RHS 75C.	60	What is claimed is:
		1. A new and distinct variety of <i>Chrysanthemum</i> plant named 'Synjac Pinka' substantially as illustrated and described herein.
